(57) **CLAIM**

The ornamental design for a vest mounted pouch, as shown and described.

DESCRIPTION

FIG. 1 is a front perspective view of the vest mounted pouch according to the present invention.

FIG. 2 is a rear perspective view of the vest mounted pouch according to the present invention.

FIG. 3 is a top view of the vest mounted pouch according to the present invention; and,

FIG. 4 is a bottom view of the vest mounted pouch according to the present invention, the other side view being identical. The small broken lines representing a hook and loop surface are for the purposes of illustrating environment and form no part of the claimed design. The evenly spaced broken lines represent stitching and are part of the claimed design.
